UNITED STATES PATENT OFFICE.

VICTOR WARNELO, OF GRAND RAPIDS, MICHIGAN.

LOCK.

Application filed June 26, 1922. Serial No. 570,779.

To all whom it may concern:

Be it known that I, VICTOR WARNELO, a citizen of the United States of America, residing at Grand Rapids, in the county of Kent and State of Michigan, have invented certain new and useful Improvements in Locks, of which the following is a specification.

This invention relates to certain new and useful improvements in locks, and has particular reference to a lock embodying a casing and a hinged shackle bolt supported thereon with a tensioned locking dog engaging the keeper end of the shackle bolt for retaining the same in locked position relative to the casing.

The primary object of the invention resides in the provision of a lock having the peculiar releasing mechanism for the shackle bolt, the shackle bolt being released by a hingedly mounted bar simulating a brace bar for the lock casing, said casing being provided with a key hole opening that does not enter into the operation of the shackle bolt.

With the above general objects in view and others that will become apparent as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a front elevational view of a padlock constructed in accordance with the present invention showing the operating bar for the shackle bolt keeper shifted to its releasing dotted line position,

Figure 2 is a sectional view taken on line II--II of Fig. 3 showing the lock casing, the tensioned shackle bolt and the pivotally mounted tensioned keeper for the shackle bolt, the shackle bolt and tensioned keeper being shown by dotted lines shifted to their releasing position,

Figure 3 is an edge elevational view of the lock,

Figure 4 is a sectional view taken on line IV--IV of Fig. 1 showing the lug carried by the operating bar for releasing the shackle bolt keeper, and

Figure 5 is a sectional view taken on line V--V of Fig. 1.

Referring more in detail to the accom-

panying drawing, there is illustrated a padlock embodying a casing comprising a rear wall 1, side and upper and lower end walls 2 and 3 respectively, the upper end wall being cut away as at 4 and 5 respectively to accommodate the pivotal mounting of one end of the shackle bolt 6 and also providing an opening for receiving the swinging end of said shackle bolt. A cover 7 is secured to the body casing by corner pins 8 shown more clearly in Fig. 2, the corner pins extending through the cover and body of the lock as shown in Fig. 5 and anchored by brace bars 9 arranged adjacent opposite ends of the lock casing.

The shackle bolt 6 is pivotally mounted upon one of the connecting pins 8 as shown in Fig. 2, and the inner end 10 of said shackle bolt adjacent said pivotal connection is bifurcated. The opposite end of the shackle bolt is provided with a hook 11 and extends through the opening 5 of the upper end wall of the lock casing.

A bell crank keeper lever is pivotally mounted within the lock casing upon the pin 12, the leg 13 thereof carrying a keeper hook 14 for engagement with the hook 11 upon the adjacent swinging end of the shackle bolt 6, the other leg 15 of the bell crank keeper lever carrying a depending lug 16 for purposes presently to appear. A band spring bent into substantially V-shaped formation is disposed within the casing, the loop 17 thereof being supported upon the pin 18, one leg 19 of said spring having the free end thereof extending into the bifurcated end of the shackle bolt 6, and engaging the pin 20 for increasing tension thereof, the other leg 21 of said spring engaging the adjacent rear face of the keeper lever leg 13 as shown in Fig. 2, moving the keeper lever upon its pivot pin 12, which movement is limited by the leg 13 engaging the pin 22.

A pivotally mounted bar 23 mounted upon the lock casing cover 7 adjacent one end thereof, in simulation of a brace bar 9 is pivoted adjacent the upper end thereof upon the pin 24 and carries a false retaining pin 25 in the lower swinging end thereof. The casing cover 7 is slotted as at 26, shown more clearly in Fig. 5, a finger 27 carried by the inner face of the pivoted bar 23 extending through said slot 26 for engagement with the depending lug or finger upon the lower leg 15 of the bell crank keeper lever. The

lock casing cover 17 is provided with a key hole opening 28 tending to confuse and in no manner effect an operation of the lock.

Assuming that the shackle bolt 6 is in the locked position shown in Fig. 1, and it being desired to release the same to permit shifting to the dotted line position shown in Fig. 2, the pivoted bar 23 is shifted to the dotted line position shown in Fig. 1, causing the finger 27 carried thereby to engage the lug 16 upon the bell crank keeper lever to shift said lever upon its pivot pin 12 and release the keeper hook 14 from engagement with the hook 11 upon the free swinging end of said shackle bolt. The outer end of the spring arm 19 being under tension by engaging the pin 20, as shown in Fig. 2, said spring arm 19 engaging the bifurcated end 10 of the shackle bolt will shift the shackle bolt upon the pin 8 and cause the same to move to the dotted line position, and when so disposed, and when pressure is relieved upon the pivoted bar 23, the spring arm 21 engaging the upper leg 13 of the keeper lever will restore the keeper lever to its set position engaging the stop pin 22 and causing the lug 16 carried by the lower leg 15 to shift the finger 27 and pivoted bar 23 to its set position shown by full lines in Fig. 1.

The key hole opening 28 is only provided for causing confusion in the operation of the lock mechanism, and in no manner enters into the operation of said lock. The lock being extremely simple in construction and inexpensive to manufacture possesses many advantages over locks of a more complicated nature, there being comparatively few parts embodying the operating mecha-

nism thereof and such parts being of a nature that are not liable to damage.

While there is herein shown and described the preferred embodiment of the present invention, it is nevertheless to be understood that minor changes may be made therein without departing from the spirit and scope of the invention as claimed.

What is claimed as new is:—

In a lock of the type described, a casing, two pairs of longitudinally extending bars carried by said casing, each pair being positioned on opposite faces of the casing and adjacent the side walls thereof, one of the bars carried by the front face of said casing being pivotally attached thereto, a shackle bolt having a bifurcated end pivoted within the casing and having a hook upon the other end adapted to enter the casing, a tensioned keeper lever pivoted within the casing engaging the hook end of the shackle bolt, and means for shifting the keeper lever to free the same from engagement with said shackle bolt hook, said means comprising a finger carried by said pivoted bar extending through a slot provided in said casing and engaging with said keeper lever for shifting the same to free the hook end of the shackle bolt, the tensioned means for said keeper lever embodying a substantially V-shaped flat spring having one leg thereof engaging the keeper lever and the other leg engaging the bifurcated pivoted end of the shackle bolt for swinging the free end of said shackle bolt outwardly of the lock casing when the keeper lever is released therefrom.

In testimony whereof I affix my signature.

VICTOR WARNELO.
